UNITED STATES PATENT OFFICE

CHARLES D. WESSELS, OF CLEVELAND, OHIO.

DRAIN-FITTING.

1,185,960.

Specification of Letters Patent. Patented June 6, 1916.

Application filed August 6, 1915. Serial No. 44,021.

To all whom it may concern:

Be it known that I, CHARLES D. WESSELS, a citizen of the United States, residing at Cleveland, in the county of Cuyahoga and State of Ohio, have invented a certain new and useful Improvement in Drain-Fittings, of which the following is a specification.

This invention relates to the connection used between sinks, tubs, or other similar 10 receptacles, and the waste-pipe or trap, and while it may be applied to any stationary tub construction, it is particularly adaptable to concrete tubs.

In the common plumbing practice as at 15 present employed, for making the drain connections from the tubs to the trap and waste-pipe, lead pipe is used and what is known in plumbers parlance as a wipe-joint is made between the drain fitting and the 20 trap, or directly with the waste-pipe when a trap is not interposed. While the wipe-joint construction may be suitable and in common use, it has objectionable features, among which are inconvenience for repairs 25 and nondurability. In many instances, particularly in high grade laundry equipment and plumbing, iron pipe is specified with more serviceable connections, therefore the objects of this invention are to 30 provide a universal drain connection that is adaptable to either the wipe-joint, lead pipe plumbing or to iron pipe and more durable joints. Another object of the invention is to provide a drain fitting that can 35 be easily and quickly connected with or disconnected from the trap or waste-pipe, thereby facilitating installation and repairs.

A valuable feature of the invention is its universal adaptability to the different 40 connections, thereby eliminating the necessity of providing a special fitting for each type of joint, therefore the present invention provides a more efficient drain connection or fitting than has heretofore been used.

To facilitate the understanding of the 45 invention reference is had to the accompanying drawings, similar characters of reference being employed to designate similar parts in said drawings and in the specification.

In the drawings Figure 1 illustrates a portion of a double, concrete, stationary laundry tub embodying the invention, showing its connection with the two compartments of the tub and with a waste trap.

Fig. 2 is a vertical section on line 2—2 Fig. 3. Fig. 3 is an underside view of the improved fitting. Fig. 4 is a transverse section on line 4—4 Fig. 3. Fig. 5 is a view partially in central vertical section, showing one kind of joint. Fig. 6 is illustrative of a lead pipe wipe-joint.

Referring to the drawings 1 is a hollow casting adapted to be set into the bottom 2 of the tub, and having branches 3 and 4 60 the chambers in which open into the compartments 5 and 6 respectively. The casting 1 is provided with a stem 7 having an opening therein which communicates with the chambers in the branches 3 and 4. The 65 exterior of the stem 7 is the form of a truncated cone as shown at 8, and the interior of said stem is threaded as at 9. On the undersides of the branches 3 and 4 are bosses 10 provided with openings 11 and ledges 12 70 for the purpose of retaining bolts, their heads being seated on the ledges 12 as shown in Figs. 5 and 6. These bosses are serviceable for certain joints as hereinafter explained.

The elongated opening 13 is provided for an insert member 14 which is adapted to be embedded in the concrete as an aid to the anchorage of the casting 1 in the bottom 2, or the said opening 13 may be used for 75 an overflow connection not shown.

If it is desired to use iron pipe, a simple and serviceable connection is made by merely threading the pipe 15 into the opening in the stem 7 as shown in Fig. 1. If lead 80 pipe and a wipe-joint is specified, the same fitting 1 may be used, the mouth of the pipe 16 being flared in the usual way and wiped around the truncated cone portion 8 as shown in Fig. 6. In the lead pipe, wipe-joint construction a collar 17 circumscribes the pipe 16 and is provided with ears 18 through which the bolts 19 project, the heads of the bolts resting on the ledges 12. 85 Through the medium of the nuts 20 on the bolts 19 the collar 17 can be drawn up against the shoulder 21 formed by flaring the pipe 16, thus securing a tight joint and supporting the pipe 16.

Fig. 5 illustrates a joint wherein the pipe 105 22 is provided with a shoulder 23 and is screwed into the stem 7, a collar 24 is drawn up against the shoulder by nuts 20 on the bolts 19, the same as in the wipe-joint construction. This forms an absolutely tight, 110

lock joint, as the thrust of the collar 24 on the shoulder 23 causes the thread on the pipe to bind in the thread 9 of the stem 7.

From the foregoing it will be seen that the same drain fitting is applicable to a variety of connections. I am aware that a drain fitting having a truncated cone stem has been used for lead pipe with a wipe-joint, but what is considered as an improvement is the universal adaptability of the present invention, thereby increasing the utility of the article.

What I claim and desire to secure by Letters Patent is—

15 1. A drain fitting for laundry tubs and the like, said fitting comprising an integral shell member having branches for connection with the compartments of the receptacle to be drained, and a stem for connection with a trap or waste-pipe, providing open communication through said branches and stem, the interior of the stem being threaded to accommodate a standard fitting and the exterior of said stem being a truncated cone.

20 2. A drain fitting for laundry tubs and the like, said fitting comprising an integral

shell casting having branches for connection with the compartments of the receptacle to be drained, and a stem for connection with a trap or waste-pipe, providing open communication through said branches and stem, bolt hangers cast on said shell, the interior of the stem being provided with a pipe thread to accommodate a standard fitting and the exterior of said stem being of truncated cone formation.

3. A drain fitting for laundry tubs and the like, said fitting comprising an integral shell casting having branches for connection with the compartments of the receptacle to be drained, and a stem for connection with a trap or waste-pipe, providing open communication through said branches and stem, bolt hangers on the underside of said branches, the interior of the stem provided with a pipe thread to accommodate a standard fitting and the exterior of said stem being of truncated cone formation.

CHARLES D. WESSELS.
